UNITED STATES PATENT OFFICE.

BENJAMIN G. LAMME, OF PITTSBURG, PENNSYLVANIA, ASSIGNOR TO
WESTINGHOUSE ELECTRIC & MANUFACTURING COMPANY, A COR-
PORATION OF PENNSYLVANIA.

ELECTRICAL MACHINE.

No. 838,034.

Specification of Letters Patent.

Patented Dec. 11, 1906.

Application filed February 21, 1905. Serial No. 246,684.

To all whom it may concern:

Be it known that I, BENJAMIN G. LAMME, a citizen of the United States, and a resident of Pittsburgh, in the county of Allegheny and 5 State of Pennsylvania, have invented a new and useful Improvement in Electrical Machines, of which the following is a specification.

My invention relates to electrical machines, 10 and particularly to machines which embody high-resistance connections between their armature-coils and their commutator-bars or between different portions of their windings.

The object of my invention is to provide a 15 machine of the character indicated in which the high-resistance conductors are so disposed as to insure certain advantages not secured by the structures and arrangements which have heretofore been employed.

20 Patent No. 758,668, granted to the Westinghouse Electric & Manufacturing Company May 3, 1904, upon an application filed by me, discloses a construction in which high-resistance leads between the armature- 25 coils and the commutator-bars of an electrical machine are located in the bottoms of the slots which contain the armature-windings and are connected to the armature-coils at the ends remote from the commutator.

30 Patent No. 780,047, granted January 17, 1905, to the Westinghouse Electric & Manufacturing Company upon an application filed by me, shows a construction similar to that of the patent just mentioned and differs from 35 what is set forth in the earlier patent in the provision of a plurality of lengths of resistance-conductor instead of a single length in order to secure the desired amount of resistance and also in case the resistance-conductor 40 is doubled once upon itself in the elimination of inductive effects. Each of the inventions covered by the above-mentioned patents constituted a distinct and practical advance in the art; but each possessed the disadvantage that the resistance-leads must be accommodated within the armature-slots, and therefore the slots must be made considerably deeper than would be otherwise required, thereby making the proportions of 45 armature-teeth and slots sometimes undesirable for the best working conditions. Furthermore, the location of the resistance-leads

in close proximity to the armature-coils involved the transfer of some of the heat generated in such leads to the coils, and thereby 55 reduced the efficiency of the latter.

In order to avoid enlargement of the core-slots beyond what is demanded for proper electrical proportions and to also avoid transference of heat from the resistance-leads in 60 the armature-coils, I propose to provide independent slots in the armature-core for the resistance-leads and to double each of such leads once upon itself, thus rendering it non-inductive. 65

Figure 1 of the accompanying drawings is a longitudinal section of one-half of an armature embodying my invention, a portion of the shaft being broken away. Fig. 2 is a face view of approximately a quadrant of one of 70 the laminae of the armature-core shown in Fig. 1, and Figs. 3 and 4 are similar views of modified forms of laminae that may be employed in armatures embodying my invention. 75

The laminated core 1 of the armature is provided with ventilating-passages 2 and is mounted upon a spider 3, which in turn is suitably secured upon a shaft 4, these parts having any form, dimensions, and arrangement that may be usual in the art or desired for any particular service. The commutator-cylinder 5 may also be of any usual or approved construction and may have its bars properly connected to the armature-coils 6 80 by means of high-resistance leads 7. The coils 6 are located and disposed in open, partially open, or closed slots 8 in the core 1 and adjacent to its surface, and the resistance-leads 7 may be connected to the commutator 90 ends of the coils 6 by means of suitable connectors 9 and each doubled once upon itself and connected at its other end directly to the proper commutator-bar of the cylinder 5. Each doubled lead 7 is placed in a slot 10, 95 which is located at any convenient distance from the outer surface of the core, and these slots are preferably disposed uniformly around the armature-axis. Inasmuch as these slots are not open to the surface of the 100 armature except at their ends, they may be made of such shape, dimensions, and number as will cause the least disturbance of the magnetic and electrical circuits of the armature.

Since there is ordinarily more available space for sheet-steel beneath the coil-slots than is actually required for magnetic purposes, the cutting away of enough material to accommodate the resistance-leads does not interfere with the proper operation of the machine. Furthermore, the disposition of the resistance-leads herein set forth possesses several distinct advantages. For example, 10 with this arrangement the resistance-leads are embedded in the interior of the core, and the heat generated in the leads is therefore transmitted to the core-laminae and disseminated more effectively than would be the case if the leads were otherwise located.

The slots for the leads may be of such form as is best adapted for transferring the heat, and the number of leads in each slot may be anything desired irrespective of the number, 20 size, or shape of the armature-slots at the surface—that is to say, the slots for the armature-coils may be of such shape and dimensions as may be required for the best operating conditions of the armature-winding, 25 while the slots for the resistance-leads may be of such other form and dimensions as will best facilitate the performance of the functions of such resistance-leads.

Figs. 2, 3, and 4 illustrate some of the various forms that the armature-laminae may assume in practice, the resistance-conductor slots being greater in number than the armature-coil slots in Fig. 2, the same in number in Fig. 3, and smaller in number in Fig. 4. 30 In order that the resistance-conductors may be distributed to best advantage among the slots provided for their reception, it is desirable that the number of slots in the inner set bear some definite relation to the number 40 at the outer periphery, and such a relation may be the inverse of the ratio of the number of conductors in the resistance-lead slots to the number in the armature-coil slots. With the arrangement shown in Fig. 2 it may 45 be assumed that each of the slots in the inner set will accommodate eight resistance-leads, and each of the slots at the outer periphery will accommodate ten armature-conductors, and therefore the numbers of slots in the two 50 sets may be in the ratio of one hundred and twenty to ninety-six, as here shown. With the structure shown in Fig. 3 it is intended that each slot shall contain the same number of conductors and with the structure shown 55 in Fig. 4 that the ratio of the number of conductors in each slot of the inner set to those in each slot of the outer set shall be as eight to six, the numbers of slots in the two sets in the latter case being ninety-six and seventy- 60 two, respectively.

Another advantage incident to this construction is that the resistance-leads may be removed, if desired, without interference with the armature-coils.

65 While I have shown and described my in-

vention as applied to a rotatable armature having its coils connected to commutator-bars, I have not restricted the structure to use in either a motor or a generator to the exclusion of the other service, since while the invention is especially useful in connection with single-phase alternating-current motors, yet there may be instances where it will be found useful in connection with generators, and I desire it to be further understood 70 that the invention is not necessarily limited to machines of the commutator type, since the arrangement of resistance leads or conductors which is here shown and described may be utilized and be effective wherever resistances are used in connection with machine-windings—as, for example, in the case of induction-motors, in which resistances are connected in circuit with either rotatable or stationary secondary windings. In such relations the resistances may be embedded in 80 their own slots in the core of the secondary member of the motor and the number and size of such slots may be made entirely independent of the number and size of the slots 85 adjacent to the surface of the core which contain the main secondary conductors:

The dimensions, location, and arrangement of parts may be varied within comparatively wide limits from what I have 95 shown, and I therefore desire it to be understood that my invention is to be construed as free from all limitations except such as may be imposed by the prior art.

I claim as my invention

1. A core of an electrical machine having one set of slots adjacent to its surface and another set of slots more remote from such surface, and conductors located in said slots, the numbers of conductors per slot being in 105 inverse ratio to the numbers of slots in the corresponding sets.

2. A core of an electrical machine having one set of slots adjacent to its surface and another set of slots more remote from such 110 surface, and conductors located in said slots, the number of conductors per slot bearing a definite relation to the ratio of the numbers of slots per set.

3. In an electrical machine, a core having 115 two concentric sets of slots and two sets of conductors located in said slots and connected together, the number in the inner set bearing a definite relation to the number in the outer set.

4. In an electrical machine, a core having two concentric sets of slots and two sets of conductors located in said slots and connected together, the numbers of conductors per slot being in inverse ratio to the numbers of 125 slots per set.

5. In an electrical machine, a core having two concentric sets of slots, a set of low-resistance conductors in the outer slots and a set of high-resistance conductors in the inner 130

slots, said sets of conductors being connected together and the numbers of conductors per slot being in inverse ratio to the numbers of slots per set.

5 6. In an electrical machine, a core having an outer set of open slots and an inner set comprising a greater number of closed slots and sets of conductors of relatively low and high resistance in the slots of the respective sets, the numbers of conductors per slot be-

ing in inverse ratio to the numbers of slots per set.

In testimony whereof I have hereunto subscribed my name this 18th day of February, 1905.

BENJ. G. LAMME.
